UNITED STATES PATENT OFFICE

164,305

PORTABLE BUILDING

Walton O. King, Mount Clemens, Mich.

Application December 26, 1950, Serial No. 13,570

Term of patent 14 years

(Cl. D13—1)

To all whom it may concern:

Be it known that I, Walton O. King, a citizen of the United States and a resident of the city of Mt. Clemens, county of Macomb, State of Michigan, have invented a new, original, and ornamental Design for a Portable Building, of which the following is a specification, reference being had to the accompanying drawing, in which:

Fig. 1 is a perspective view of a portable building showing my new design the view disclosing one end and one side of the building, the other side and the other end having a similar appearance;

Fig. 2 is a front elevational view thereof.

I claim:

The ornamental design for a portable building, as shown and described.

WALTON O. KING.
